United States Patent Office.

ROBERT R. CAMPBELL, OF LOWELL, MASSACHUSETTS, ASSIGNOR TO LOWELL MANUFACTURING COMPANY, OF SAME PLACE.

Design No. 4,333, dated September 6, 1870.

DESIGN FOR A CARPET-PATTERN.

The Schedule referred to in these Letters Patent and making part of the same

all whom it may concern:

Be it known that I, ROBERT R. CAMPBELL, of the y of Lowell, county of Middlesex and State of Massachusetts, have invented and produced a new and orig-Design for a Pattern to be inwrought into Three-y, Ingrain, and other Carpeting, in such colors as y be desired; and I do hereby declare that the photographic print accompanying this specification does ve and convey, to any one skilled in the art of cart-weaving, a more definite and thorough description the nature of my invention than it is in the power language otherwise to convey, and it is sufficient to enable any one skilled in the art of carpet-weaving to use my invention.

Claim.

What I claim as my invention, and desire to secure by Letters Patent, is—

The configuration of the design hereunto annexed when made by being inwrought into three-ply, ingrain or other carpeting, in the form similar to the photographic print accompanying this specification.

Witnesses: R. R. CAMPBELL.
